CLAIM

The ornamental design for a combined golf divot tool and ball marker, as shown and described.

DESCRIPTION

FIG. 1 is a front elevational view of the combined golf divot tool and ball marker showing my new design;

FIG. 2 is a front elevational view with the ball marker removed;

FIG. 3 is an exploded top perspective view, with the rear view of the ball marker being a mirror image thereof;

FIG. 4 is a left side elevational view with the ball marker removed; and,

FIG. 5 is a rear elevational view of FIG. 2.

The claim is directed to the collective appearance of the combined golf divot tool and ball marker shown in the figures. The components of the set are arranged on the drawing sheet for the convenience of illustration, and the relative positioning of the combined golf divot tool and ball marker forms no part of the claimed design.
